UNITED STATES PATENT OFFICE.

SYLVANUS T. MURCHIE, OF BATAVIA, ILLINOIS, ASSIGNOR TO THE UNION PAPER BAG MACHINE COMPANY, OF PHILADELPHIA, PENNSYLVANIA, A CORPORATION OF PENNSYLVANIA.

CUT-OFF MECHANISM.

SPECIFICATION forming part of Letters Patent No. 739,555, dated September 22, 1903.

Application filed July 3, 1899. Serial No. 722,628. (No model.)

To all whom it may concern:

Be it known that I, SYLVANUS T. MURCHIE, of Batavia, in the county of Kane and State of Illinois, have invented certain new and useful Improvements in Cut-Off Mechanism, of which the following is a specification.

This invention relates to a cut-off mechanism for use in apparatus operating with air or other fluids under pressure, and is particularly adapted for use in connection with air-suction rolls, such as are employed in paper-making, bag-machines, and the like.

An illustration of the class of machines to which my invention is particularly applicable is the paper-bag machine shown in Letters Patent No. 585,280, granted to me June 29, 1897. In the paper-bag machine of that patent a flat tube of paper, having tucked-in sides, has its leading end opened by passing it between two perforated rolls or cylinders from whose interior the air is exhausted, the exhaust being cut off at suitable intervals by means of a gate or valve in the trunk or pipe leading to the exhaust-fan. The gate or valve is there shown as being operated by a rod and has a rocking or oscillating movement.

My present improvement—the cut-off mechanism—is of a rotary type; and it consists, essentially, in the combination, with the pipe through which the air or other liquid is moved, of a rotary valve or gate in the form of a disk, having a slot or aperture therein concentric with the axis of the disk, with suitable gearing for rotating the disk, so as to cover and uncover the pipe through which the air is passing, thus cutting off the exhaust or blast, as the case may be, at regular intervals, which may be timed so as to operate in due order and relation to the other parts of the apparatus.

In the accompanying drawings I have shown my invention embodied in a cut-off mechanism for controlling three pipes or passages, the several cut-off valves being geared to operate in unison.

In the drawings, Figure 1 is an elevation showing the valve-disks and their gearing in edge view and the pipes and an air-box with which they connect. Fig. 2 is a side view of the parts shown in Fig. 1, showing an end view

of the pipes and a side view of the valve-disks and gears. Fig. 3 is a sectional elevation on line 3 of Fig. 1 looking toward the valve-disks.

In the present embodiment of the invention three suction-pipes 5, 6, and 7 are shown, all of which connect with a common air-box 8, having a suction connection or flange 9. With the pipes 5, 6, and 7 are connected other pipes 10, 11, and 12, respectively, which may be in communication with suction-rolls, suction-boxes, or other chambers from which air is exhausted or into which it is delivered under blast. The pipes 5, 6, and 7 are interrupted or cut across between their ends, the outer ends 5^a, 6^a, and 7^a being supported by the standard 13, which also affords a support for studs 14, carrying pinions 15, 16, and 17, and valve-disks 18, secured by collars 19 and nuts 20. The valve-disks 18 may be thin metal plates and are each provided with apertures 20^a concentric to their axes. The valve-disks are arranged with such reference to the two sections of the suction-pipes that the apertured portions of the disks will register with the bore of said pipes during each complete rotation of the valve-disk. The disks may all be driven in unison from the pinion 20, enmeshed with the pinion 15, driving the intermediate gear 21, which in turn, through the pinion 16 and intermediate gear 22, drives the pinion 17. As shown in Figs. 2 and 3, the pipe 5^a is cut off by the solid portion of the valve 18, while the pipes 6 and 7 are in open communication through the aperture in their valves 18. The pipe-sections 5 5^a abut so closely against the opposite sides of the revolving disk as to make a sufficiently close joint, the lateral edges or walls of the aperture extending practically into the bore of the pipe, so as to maintain the joint.

While I have shown a series of cut-offs geared together and while such application would be particularly adapted to a machine using a number of suction-rolls—such, for example, as the machine shown in my patent above mentioned—I do not limit my invention to the employment of a series of cut-offs geared or otherwise connected or co-operative.

When the cut-off mechanism is used in, say, a bag-machine, its gear may be driven in unison with and in due relation to the functions of the suction-cylinders, which open the leading end of the tube, and obviously this form of cut-off is particularly adapted to be used in all situations where the effect or function of a fluid under pressure is to be temporarily arrested and in due relation to some moving part of the machine. Obviously, also, the cut-off could be used in conjunction with an air-blast as well as with suction. The disks and gears are preferably loosely mounted upon the short studs or shafts, and the nuts offer means for clamping them in any desired position of adjustment. By reference to Figs. 2 and 3 it will be seen that the upper valve is in position to cover the passage, while the two lower valves are in such position that their apertures register with the air-passages. These positions may be varied or altered at will.

Without therefore limiting my invention to precise details of construction, arrangements of parts, or specific uses, I claim—

A cut-off mechanism comprising in combination, a pipe or passage having its body portion intersected intermediate its length, the opposing ends of said body portion closely adjacent to, and in direct alinement with, each other, a disk of substantially uniform thickness mounted upon an axis to rotate in the plane of, extend into and substantially occupy the space formed by, said intersection, its sides contiguously engaging said opposed ends, an aperture in said disk eccentric to its axis of rotation intermittently registering with, and directly continuing, the passage of the pipe, and means for rotating said disks, whereby the passage through the pipe is alternately opened and closed and the pipe is at all times substantially closed against escape from, or egress to, its interior at said intersection, substantially as shown and described.

SYLVANUS T. MURCHIE.
